UNITED STATES PATENT OFFICE.

CHARLES A. GUNZELMAN AND WILLIAM J. GUNZELMAN, OF ABILENE, KANSAS.

CARD SHUFFLER.

Application filed June 22, 1925. Serial No. 38,870.

To all whom it may concern:

Be it known that we, CHARLES A. GUNZELMAN and WILLIAM J. GUNZELMAN, both citizens of the United States, and residents of Abilene, in the county of Dickinson and State of Kansas, have invented a new and useful Improvement in Card Shufflers, of which the following is a full, clear, and exact description.

10 Our invention relates to improvements in card shufflers, and it consists in the combinations, constructions, and arrangements herein described and claimed.

An object of our invention is to provide a card shuffler that is adapted to receive 15 a deck of cards and to thoroughly mix the cards in the deck, this being accomplished by a mechanical means that is brought into play when the device is shaken by the operator.

20 A further object of our invention is to provide a card shuffler in which the box is shaped so as to aid in the shuffling of the cards.

A further object of our invention is to 25 provide a card shuffler which is simple in construction, durable and thoroughly efficient for the purpose intended, and which is not likely to get out of order easily.

Other objects and advantages will appear 30 in the following specification, and the novel features of the invention will be particularly pointed out in the appended claims.

Our invention is illustrated in the accompanying drawings, forming part of this application, in which

35 Figure 1 is a top plan view of the device, and

Figure 2 is a longitudinal section through the device.

40 In carrying out our invention we provide a card shuffler that comprises a box having the shape shown in Figure 2. It will be noted from Figure 2 that the top 1 and the bottom 2 of the box are narrower than the distance across the middle of the box.

45 When the cover 3 is in closed position, the box entirely encloses the deck of cards. In use the deck is first placed in the top of the box and here the wall 4 and the door 3 contact with the deck so as to hold the ends 50 of the cards at the top of the deck in close proximity to each other while at the same time permitting the cards to flare outwardly

at the other end of the deck. The slanting wall 4 and the slanting door 3 permit the 55 cards to assume this position.

Of course the cards are not clamped to the top of the box but are permitted to drop by gravity to the other end of the box. The cards when in the lower end 2 of the 60 box are held by the sides 5 and 6 of the box so as to cause the deck to represent an inverted triangle.

We provide means for preventing all of 65 the cards from moving from the top of the box to the bottom of the box at the same time. This means in the present instance consists of card mixing members 7 and 8 that are pivotally mounted at 9 and 10 to the sides of the box. The members are in the shape of a vane and are adapted to interfere with the movement of the cards from the upper to the lower compartment or vice versa. We have found that the best results 70 are obtained by spacing the centers of the vanes three-fourths of an inch apart. There is still space between each of the vanes and between the vanes and the sides of the box. The vanes will not remain in the position shown in Figure 2 but will be turned into various positions as the cards pass thereby.

75 From the foregoing description of the various parts of the device, the operation thereof may be readily understood. The box is preferably made out of bakelite or other similar material and is lined with a soft material such as felt or the like. The cover 3 is hinged at 11 and is spring pressed so as to be yieldingly held in closed position. It will be noted that the top 1 has a slot 12 80 cut therein, this slot extending into the wall 4 for a short distance.

85 When operating the device the door 3 is opened and the deck is inserted into the box. The box is preferably held in a horizontal position when inserting the deck of cards. The slot 12 is for the purpose of permitting the fingers of the player to keep hold of the cards while placing the cards in the box. The deck is placed in the box so as to have the face of the cards turned toward the wall 4. The door is now closed 90 and the box is grasped in the hand of the operator and held in a vertical position while the box is moved up and down. The position of the box may be changed but we have 100 105

found the best results are obtained when the box is held in vertical position and reciprocated in a vertical plane.

- While the box is being moved gravity 5 will cause the cards in the deck to drop from the upper compartment to the lower compartment. As heretofore stated, the deck when in the upper compartment has the lower end thereof flared so as to cause the 10 cards to take different paths in passing from the upper compartment to the lower compartment. Moreover the vanes 7 and 8 prevent the entire deck from passing from the upper compartment to the lower compartment at the same time. The vanes are rotatably mounted and therefore cut into the 15 deck so as to deflect the cards as they pass by the vanes, thus effectually mixing the cards.
- 20 When the cards are all in the lower compartment the box is inverted and the same operation repeated. The cards in passing from the point adjacent to the wall 2 to the point adjacent to the wall 1 will be mixed 25 still further. A window 13 is provided in the wall 6 so as to permit the player to tell when all of the cards in the compartment adjacent to the window 13 have passed therefrom into the next compartment. When 30 the cards are all in the compartment covered by the door 3, the operator knows that the

cards are mixed and can then open the door, grasp the deck in his hand and remove the deck from the box. The slot 12 permits the deck to be readily removed.

35

We claim:

1. A card shuffling device comprising a casing adapted to receive a deck of cards, and means disposed in said casing for shuffling the deck of cards, said means being 40 actuated by the movement of the cards.

2. A card shuffling device comprising a casing adapted to receive a deck of cards, means disposed in said casing for shuffling the deck of cards, said means being actuated 45 by the movement of the cards, and a window disposed in said casing to permit the player to see the cards.

3. A card shuffler comprising a casing divided into card receiving compartments, the 50 walls of said compartments being inclined so as to bring the edges of the cards adjacent to one end of the deck in close proximity to each other, while permitting the opposite edges of the cards to be spaced from 55 each other, and means disposed in said casing for shuffling the deck of cards, said means being actuated by the movement of the cards.

CHARLES A. GUNZELMAN.
WILLIAM J. GUNZELMAN.
